UNITED STATES PATENT OFFICE.

WALTER HEDLIND, OF PORTLAND, OREGON.

VENDING MACHINE.

Application filed April 2, 1926. Serial No. 99,369.

My present invention has reference to a coin controlled display and dispensing apparatus.

An object is the provision of an apparatus especially designed for vending fruits but of course, susceptible for vending other articles, and my improvement contemplates the employment of yieldable compartments so that articles may be arranged in super-
10 relation therein without liability to injury, and wherein means is employed for singly delivering the articles from the outer compartment and thereafter for delivering or dispensing the several articles in the compartments to the rear of said outer compartment.

A still further object is the provision of a vending apparatus including yieldable compartments in which the articles to be vended are arranged one on the other, and wherein the outlet to the outer or front compartments are closed in a novel manner, the said closures being swung, upon the actuation of suitable mechanism to arrange the article
25 contacted thereby in delivery position, means also contacting with the article and forcing the same to such delivery position and likewise holding the remaining articles in the compartments from dropping in the compartment to delivery position.

A still further object is the provision of a coin controlled vending apparatus in which articles are arranged in compartments that comprise yieldable rod members, the said articles being visible through transparent openings in the casing of the device, the several compartments being disposed one to the rear of the other, swingable gate means preventing the entrance of the articles from one into the other compartments until the last mentioned compartments have been emptied, means normally closing the outlet to the front compartment, means actuated by the insertion of a coin swinging the closing means to open position and likewise actuating mechanism to swing a retarding device beneath the article directly above that which has been brought to delivery position.

A still further object is the provision of a display and vending apparatus for fruits or the like that is characterized by simplicity in construction, cheapness in manufacture and thorough efficiency in practical use.

To the attainment of the foregoing and other objects which will present themselves as the nature of the invention is better un-

derstood, the improvement further resides in the combination, and operative association of parts, a satisfactory embodiment of which is illustrated by the drawings which accompany and form part of this application.

In the drawings:

Figure 1 is a front elevation of a vending apparatus in accordance with this invention.

Figure 2 is a sectional view approximately 65 on the line 2—2 of Figure 1.

Figure 3 is a detail sectional view illustrating the lower part of the construction disclosed in Figure 2, but showing the arrangement of elements when an article is 70 to be delivered.

Figure 4 is a sectional view approximately 75 on the line 4—4 of Figure 2.

Figure 5 is a side elevation of one of the compartment closing devices and the elements associated therewith, parts being in section.

Figure 6 is an approximately vertical longitudinal sectional view through the coin receiving device.

Figure 7 is a sectional view approximately 80 on the line 7—7 of Figure 6.

Figure 8 is an approximately sectional view on the line 8—8 of Figure 6.

Figure 9 is a detail perspective view to 85 more fully illustrate the arrangement of parts, as disclosed by Figure 2 of the drawings.

Figure 10 is a similar view to better illustrate the arrangement of parts, as shown in 90 Figure 3 of the drawings.

In carrying out my invention I make use of a substantially rectangular casing which is broadly indicated by the numeral 1. The casing has an open top, provided with a 95 hinged cover 2 which is locked thereon in any desired manner. The front and rear faces of the casing, at a suitable distance from the bottom thereof, are provided with openings which are closed by transparent 100 plates 3.

In the casing there is any desired number of article receiving compartments. In the showing of the drawings six series of compartments are employed, and each series 105 comprises three compartments disposed one to the rear of the other. As all of the compartments are of a similar construction, reference will be made to only one series thereof.

110 All of the compartments are made up of four rightangularly arranged spring rods

4. The lower ends of the rods are headed, as at 5, and the said rods are passed through suitable openings in the base 6 of the case. The upper ends of the rods are provided with eyes 7 and these eyes pass through rods 8 which are arranged transversely in the case and which have their ends secured to the front and rear walls of the said case. On each of the rods 8, there are fixed stop elements 9, and surrounding the rods and exerting a pressure between the stop elements and the eyes 7 of the spring rods 4 there are light coiled springs 10.

In the case 1 there is a floor or partition 11 that provides the bottom of the several compartments. It may be well to separately refer to the several compartments, and therefore the front compartment is indicated by the numeral 12, the intermediate compartment by the numeral 13 and the rear compartment by the numeral 14. The base plate 11 extends the entire length and width of the case 1, and is arranged at a downward inclination from its connection to the back of the case to a point through which the front rods 4 of the intermediate compartment 13 pass. From thence the base 11 is extended downwardly at a more determined angle, as indicated by the numeral 15. The angle portion is rounded and extended at a downward and outward angle, as at 16, to its connection with the front of the case 1. The rods constituting the compartment 12 pass through the portions 16 and the mentioned rounded portion of the base 11.

Pivoted, as at 17 and 18, respectively, between the compartments 12 and 13, and 13 and 14, there are flat plates 19 and 20, respectively. These plates are in the nature of valves, the pivot 18 being disposed below the pivot 17, and each of the valve plates 19 and 20 is provided with an angle extension 21 and 22, respectively, that is arranged forward of but between the front bars 4 of the compartments 13 and 14. The angle elements 21 and 22 serve as stops for the fruit or similar articles 23 which are arranged one on the other in the compartments 13 and 14. The compartments are filled with fruit by opening the closure 2 and the fruit or other articles in the several series of compartments may be of the same or of different natures. The lower of the superimposed fruit in the compartment 12 is indicated for distinction by the numeral 24, and this fruit rests upon the rounded connecting wall 25 between the angle portions 15 and 16 of the inclined partition 6 or base 11. It is obvious that were not means provided for holding the fruit 24, the latter would gravitate over the inclined surface 16 and would be delivered through an opening 26 in the front of the case 1.

This movement of the fruit is prevented

in a manner which will now be described.

Below the inclined end portion 16 of the base 11, there are mounted in suitable bearings at the ends of the case, spaced shafts 28 and 29, respectively. The fruit or article retarding elements are all of a similar nature but, of course, only one is employed for closing each of the outlet openings 26. Each of these members comprises an arched plate 30 having an inner flange 31. The flange is centrally formed with a curved tongue 32 directed toward and secured on the shaft 29. The arched retarding members 30 are swingable through a suitable opening 33 in the part 16 of the base 11. On the shaft 29, at one side of each of the series of compartments, there is fixedly secured a link 34. This link is provided with an elongated slot 35 and with a lateral notch 36 that communicates with the slot adjacent to the outer end of the link. In the slot 35 there is received a finger or an offset and rounded end 37 of a bell crank lever 38. Each bell crank lever is pivotally supported on a suitable upright 39 that is secured to the bottom 6 of the case. The vertical arm of the bell crank lever 38 is slotted, and passing through this slot there is a pivot 40 on one end of a slideable actuating rod 41. It will be apparent that when the rod 41 is moved to one position the bell crank lever will turn the shaft 29 to bring the member 30 to obstructing position and to likewise close the outlet 26. Should an attempt be made to surreptitiously swing the obstructing member 30 downwardly or to open position, the shaft 29 will be partly swung to bring the pin or offset end 37 of the bell crank lever into the notch 36. This arranges the pin 37 approximately in a plane with the pivot 42 for the bell crank lever, preventing the swinging of the said bell crank lever and consequently the opening of the obstructing member or closure 30.

Fixed on the shaft 28, approximately in a line with the sides of the tongue 32 of the obstructing and closure member 30, there are curved arms 43 respectively. These arms have their outer ends offset to provide curved fingers 44. The part 15 of the base 11 is slotted in a line with the arms 43, and their fingers 44. On the shaft 29, opposite each of the series of compartments in the case 1 there are fixed plates 45. To each of these plates there is pivoted a link 46. To each link there is pivoted a second link 47 that is fixedly secured on the shaft 28. By this arrangement it will be noted that when the operating rod 41 is moved longitudinally to bring the combined cover and article obstructing member 30 to non-covering and non-obstructing position the arms 43 will be swung upwardly into the compartment 12 so that their fingers will engage the

fruit or article 48 which has rested on the article 24 and it will be further noted that the ejecting means, comprising the said arms and fingers are actuated to engage with the article 48 before the holding member and closure has been brought to fully open position.

The rods constituting the compartments 12 and 13 have their portions directly above the base sections 11 and 16 bulged or rounded outwardly, as at 49, so that the lowermost fruit will gravitate from one into the other compartments, and this is also true with respect to the front members or rods for the rear compartment. The fingers on the ejectors serve as a rest for the fruit in the front compartment until after the lowermost fruit in the said front compartment has been ejected, and the gate valves 19 and 20 can not move to open position as long as they are in contact with the fruit in the several compartments.

It is an object to dispense the fruit upon the deposit of a coin of a determined denomination or value, and therefore the actuating rods 41 are mounted for slideable movement in casings 50 at the front of the main case 1. The actuating rods 41 are influenced each by a plunger 51, the said plunger being provided with a slot or opening in a line with a coin receiving chute 52, and each plunger being influenced outwardly by spring means 53. When a coin 54 is received in the mentioned opening in the plunger 51 and the latter is moved inwardly the said coin will contact with the inner and preferably beveled end of the actuating rod 41 to move the same longitudinally through the casing 50 to swing the bell crank lever 38. The bell crank lever is influenced by a spring 55 which is attached thereto and to the casing 50.

It is believed that when the foregoing de-

scription is carefully read in connection with the accompanying drawings that my construction and the operation thereof will be readily apparent to those skilled in the art to which such inventions relate, but it is to be understood that I do not wish to be restricted to the precise details of construction herein set forth and hold myself entitled to make all such changes therefrom as fairly fall within the scope of what I claim.

Having described the invention, I claim:— 55

1. A fruit dispensing cabinet, having vertically arranged rods therein providing compartments for superimposed fruits and said rods having their lower portions rounded outwardly to permit of the fruit from one compartment gravitating into the adjacent compartment, an inclined base on which the lower fruit rests, hinged valves between the compartments contacting the fruit therein to prevent the entrance of fruit from one to 65 the other compartment, and means controlling the outlet of fruit from the outer compartments.

2. A fruit dispensing cabinet having an inclined base therein, vertically disposed 70 rods arranged in series of four and each series comprising a fruit compartment, spring means influencing the rods toward each other for sustaining the same in parallelism, said rods, in a line with the base, 75 being bulged outwardly to provide fruit passages from one to another compartment, swingable gate valves between the inner compartments, movable through said compartments and normally held from such 80 movement by contact with the fruit in the compartments, and means controlling the outlets of the outer compartments.

In testimony whereof I affix my signature.

WALTER HEDLIND.
